STOCK FEEDING AND HANDLING APPARATUS FOR ROLLING MILLS

Jerome R. George, Marion, Mass.

Application October 21, 1936, Serial No. 106,840

9 Claims. (Cl. 80—47)

The present invention relates to rolling mills, particularly to two-high mills wherein the stock, by successive passes between the two cooperating rolls of the mill is reduced to thin sheet or strip form.

Heretofore, in sheet or strip rolling in such two-high mills, hand labor was depended upon, almost entirely, to procure the successive presentations of the stock, either in single pieces or in 10 packs of partially reduced sheets, to the rolls, a large crew of men being required at the delivery side of the mill to seize the stock upon its emergence from the rolls and to manipulate it around to the receiving side of the mill for each subsequent pass of same between the rolls.

Attempts have been made to substitute machinery for hand labor to obtain these necessary repeated manipulations of the stock in two-high sheet or strip rolling, but to a large extent 20 such machinery has proven too complicated and expensive to be practical. In some instances, tilting or reciprocating tables have been employed, but these are open to the serious objection that only one piece or one pack of pieces can be 25 handled at a time. Consequently, with these tilting or reciprocating tables, there is imposed a very considerable handicap on the tonnage capacity of the mill. An object of my invention is to overcome this handicap, by arranging for two 30 pieces or two packs of pieces to be handled in the mill at the same time.

By my invention, mechanical tables located 35 respectively at the entrance side and the delivery side of the mill, are so operated as to handle two pieces or packs of pieces simultaneously; that is to say, while one piece or pack is being passed through and between the rolls, another piece or pack is moving back over the rolls into a position 40 to follow the first-named piece or pack through said rolls in quick succession. My invention provides for such operation by handling mechanism which is relatively simple in construction and rapid and sure in operation; other and further objects and advantages of the invention will be 45 made apparent by the following detailed description thereof, reference being had in this connection to the accompanying drawings, in which—

Fig. 1 is a schematic view, illustrating in side elevation, a two-high sheet or strip mill, provided on each side with manipulating apparatus in accordance with my invention.

Fig. 2 is an end elevational view of the apparatus shown at the right side of Fig. 1.

Fig. 3 is a plan view on an enlarged scale of 55 such apparatus.

Fig. 4 is a large scale fragmentary view, in end elevation, illustrating the driving devices and connections for the stock-handling tables.

Fig. 5 is a detached side view of a certain cam. Like reference characters refer to like parts in 5 the different figures.

Referring first to Figs. 1 and 2, a two-high mill for sheet or strip rolling is indicated conventionally by the cooperating upper and lower rolls 1 and 2 respectively, both suitably journaled in the sides 3, 3 of a housing 4. The mill provides the usual screw-down devices 5, 5 for the upper roll 1, these devices, after each reduction effected on the stock by its passage between the rolls, being operated in the usual way to diminish the spacing between said rolls so as to get a further reduction of the stock on its next pass through the rolls, and so on until the stock has been rolled down to the desired thinness.

With the rolls 1 and 2 arranged to be driven 20 continuously by any suitable means, not shown, in the directions shown by the arrows thereon, the passage of the stock between said rolls is from left to right, Fig. 1, the stock, according to my invention, being fed each time to the reducing pass 25 from the mechanical handling apparatus marked A on the left hand side of the mill, and after each reduction being received by similar handling apparatus marked B on the right hand side of the mill; as hereinafter described, the stock, after 30 each reducing pass made thereon, is returned from apparatus B to apparatus A, this return movement from right to left, as to one partially-reduced piece or pack of pieces, occurring while another similar piece or pack of pieces is moving 35 in the opposite direction from left to right between the rolls.

As shown in the drawings, the devices A and B are substantially identical in construction, each 40 consisting of a structure which, by its step-by-step rotation about a horizontal axis offset from the mill and at right angles to the roll axes, is adapted to dispose, both at the reducing pass level and at the level on which the stock makes its aforesaid return movement, a succession of stock-receiving tables or conveyors, each a part of said 45 rotary structure and occupying a more or less radial relation to its axis of rotation. In each such structure, a suitably journaled horizontal shaft 6, offset as aforesaid from the line of stock travel, has secured near its opposite ends the companion hub members 1, 1', each of the latter providing in equidistant relation about its periphery, the pairs of radial ears 8, 8, there being shown, in the present instance, on each hub 50 55

member six pairs of said ears 8, 8, corresponding to the six stock-receiving tables or conveyors used in each of the devices A and B.

The two hub members 7, 7' carry between them all six of the stock-receiving tables 9, 9, each of the latter having an elongated frame portion 10, provided at opposite ends with arms 11, 11' that are received between and pivotally connected to matching pairs of ears 8, 8 of hub members 7, 7'. Each table 9 consists, as shown, of a pair of endless conveyor chains 12, 12, running over suitable idler sprockets 13, 13 at the inner end of the frame portion 10, and running over driving sprockets 14, 14 at the other end, the latter being secured to a shaft 15, suitably journaled in the frame 10 and carrying on one end a bevel gear 16. The gear 16 is in mesh with and is adapted to be driven from a bevel pinion 17 which is carried by a shaft 18, whose axis 18 coincides with the pivotal axis on which arm 11' of the table frame is connected to the ears 8, 8 of hub portion 7'; in this way, each table 9 is permitted to have pivotal movement relative to the supporting hub portions 7, 7' without interfering in any way with actuation of its conveyor chains 12, 12 by the associated driving shaft 18. The drive of shaft 18, in the case of each table, is through spur gearing 19, 20 from the shaft of a reversible electric motor 21, all six of said motors (one for each of the tables 9, 9) being suitably supported between the hub portions 7 and 7' of the rotary structure, (Fig. 4).

The shaft 6 of each rotary structure A, B is connected through suitable reduction gearing 22 to its own individual driving motor 23, the two motors 23 being so operated, through any suitable control devices, not herein shown, but well known in the art, as to cause step-by-step rotation of their respective rotary structures A and 40 B. The structure B has its intermittent rotation in the direction of the arrow b, Figs. 1 and 2, a complete revolution of such structure occurring, for the apparatus as shown, in six equal steps, with suitable periods of dwell between such steps. 45 The other structure A is similarly rotated step-by-step from its motor 23 in the opposite direction from arrow b, i. e., in the direction shown by arrow a in Figs. 1 and 2, the result being that each table 9 of apparatus A will approach its operative position in the plane of the reducing pass by a downward movement, whereas each table 9 of apparatus B will approach its operative position in the plane of the reducing pass by an upward movement.

As best shown in Fig. 2, the frame portion 10 of each table 9 has an extension 24 at the end of which is suitably journaled a roller 25; preferably, there are two such roller-equipped extensions for each table, one at either end of said table's elongated frame portion 10, as shown in Fig. 5. All six of the rollers 25 at each end of the tables are adapted to run on a cam track 26 provided by a stationary member 27 at each end of the apparatus A and at each end of the apparatus B. For the apparatus B, each cam track 26, as shown in Fig. 2, may be substantially concentric with the associated shaft 6, except for that portion thereof which controls the angular positions of the tables as they move upwardly toward and through the planes of the reducing pass and of the stock's return movement; at this portion, the cam track 26 is of the irregular form indicated at 28, the purpose of said form being to shift the tables about their pivotal connections to the hub members 7, 7'

so as to dispose said tables in each of the two planes above mentioned substantially horizontal, as clearly shown in Fig. 2. The stationary cam tracks 26, 26 for the apparatus A which rotates in the opposite direction to the apparatus B, are of the same form but in the reverse relation, as shown in Fig. 5, in order to provide for substantially horizontal disposition of the downwardly moving tables 9, 9 of apparatus A as said tables approach and pass through the planes of the 10 stock's return movement and of the reducing pass.

Each of the tables 9, 9 of the stock-feeding apparatus A is preferably equipped with adjustable side guards 29, 29 alongside the conveyor 15 chains 12, 12, each of said side guards being carried by a pair of parallel-motion rocker arms 30, 30 which are operable by a single lever 31 to move the side guards toward each other or away from each other, as desired. In this way, a plurality of superposed sheets about to enter the reducing pass of the mill can have their side edges substantially matched up or aligned by inward movement of the two side guards, following which the said side guards are moved outwardly so as to free the sheets for movement by the table's conveyor chains 12, 12. Preferably, to assist the latter in feeding the stock to the reducing rolls, the mill housing, in the plane of the pass, is equipped with a pair of conveyor 30 chains 32, 32, and similar chains 33, 33, running in the same direction, are preferably provided on the delivery side of the mill housing in the plane of the pass. Also, said mill housing in the plane of the stock's return movement is equipped 35 with pairs of conveyor chains 34, the latter running in the opposite direction from the chains 32 and 33.

The ability of the apparatus, as above described, to handle two pieces or packs of pieces 40 at a time, and to obtain repeated reductions of same by passage in quick succession from left to right between the rolls 1 and 2, is best shown by the diagram, Fig. 1, wherein, let it be assumed, that the stock marked c, after a single passage 45 between the rolls, has run out onto the horizontally disposed table 9^{b1} of apparatus B; this particular table, by the ensuing rotative movement of apparatus B, has been carried upwardly to the level of the conveyor chains 34, and at the same 50 time, other stock marked d, as yet unreduced, has been delivered from the heating furnace onto that table 9^{a1} of apparatus A which is then positioned horizontally in the plane of the reducing pass. During the dwell of the two devices 55 A and B in the positions illustrated, the associated electrical control devices, not shown, for the several motors 21, 21 are automatically rendered operative to produce actuation of the two driving motors for said tables 9^{a1} and 9^{b1}; the former, by its motor, is run in a direction to feed the stock d into the mill, and the latter, simultaneously, is run in a direction to deliver the stock c onto the chains 34, 34. As a result, during this period of dwell of the devices A and B, 60 the stock c is delivered onto table 9^{a2}, (whose chains 12, 12 are at this time driven in the same direction as chains 34), while the stock d emerging from the rolls is delivered by chains 32 onto table 9^{b2}, whose chains at this time run in the 65 same direction as the chains 32. At or before the termination of the dwell period, the several running table chains 12, 12 are brought to rest through the motor controls above referred to; thereupon, through the motors 23, 23, the devices 70

75

A and B are rotated simultaneously through one step, thus disposing the table 9^{a2} (carrying stock c) at the pass level, and disposing table 9^{b2} (carrying stock d) at the level of chains 34, i.e., 5 the stock return level. In the dwell of the devices A and B in this position, the motor control produces actuation of table 9^{a2} for the delivery of stock c to the mill and, simultaneously, the actuation of table 9^{b2}, for the return movement 10 of stock d onto table 9^{a3} of device A. The operation of the apparatus continues in this fashion for the several reductions effected in rapid succession on stock c and on stock d, until such stock has been rolled down to the desired thinness, either in single pieces or in packs of pieces 15 superposed one upon the other; then, after the removal of such reduced stock from the apparatus, two more pieces or packs of pieces are successively conveyed into the apparatus from 20 the heating furnace, and are manipulated back and forth between devices A and B in the same manner as above described to obtain successive reductions of said stock by the mill.

It is to be noted that in the above-described 25 manipulation of the stock by the apparatus of my invention, the movements of all the stock-supporting tables are uniform in direction, there being no necessity at any time for producing a reverse or return movement of any such stock- 30 manipulating device. This contributes materially to smoothness of operation and long life of the apparatus. Furthermore, by the provision of both the feeding tables and the receiving tables in multiple, for successive presentations to the working positions, there is only a 35 minimum period of exposure of each table to the heat of the stock; in this way, the apparatus avoids any possibility of warping or otherwise damaging the stock-manipulating devices 40 through overheating.

I claim:

1. Apparatus for repeatedly passing pieces or 45 packs of pieces through a sheet or strip mill, comprising in combination with the mill rolls, a set of stock receiving and feeding tables on both sides of said rolls, mountings for each set which maintain the tables thereof substantially horizontal in their operative positions, means for imparting in unison to the tables of one set a 50 succession of step-by-step movements that dispose each table successively at the pass level and thereafter on the next step at a higher or stock-return level, and means for imparting in unison to the tables of the other set a succession of 55 step-by-step movements that dispose each table successively at said higher or stock-return level and thereafter on the next step at said pass level.

2. Apparatus for repeatedly passing pieces or 60 packs of pieces through a sheet or strip mill, comprising in combination with the mill rolls, a set of stock receiving and feeding tables on both sides of said rolls, a rotary support for each set of tables, each support having its axis of rotation substantially parallel to but laterally offset 65 from the longitudinal center line of the mill, and means for imparting step-by-step rotations, substantially in unison to both supports, one in a direction to elevate each of its tables in succession from the pass level to a higher or stock- 70 return level, and the other in a direction to lower each of its tables in succession from said higher level to the pass level.

3. Apparatus for repeatedly passing pieces or 75 packs of pieces through a sheet or strip mill, comprising in combination with the mill rolls, a

set of stock receiving and feeding tables on both sides of said rolls, means for imparting to the tables of one set a step-by-step movement in a substantially circular path that carries each table with out end-to-end reversal thereof successively 5 into roll pass registry position and then into stock-return level position, and means for imparting to the tables of the other set a step-by-step movement in a substantially circular path that carries each table without end-to-end reversal thereof successively into stock-return level 10 position and then into roll pass registry position.

4. Apparatus for repeatedly passing pieces or 15 packs of pieces through a sheet or strip mill, comprising in combination with the mill rolls, a set of stock receiving and feeding tables on both sides of said rolls, means for imparting to the tables of one set a step-by-step movement in a substantially circular path that carries each table with in successive steps into roll pass registry position 20 and then into stock-return level position, means for imparting to the tables of the other set a step-by-step movement in a substantially circular path that carries each table in successive steps into stock-return level position and then 25 into roll pass registry position, and means for holding said tables substantially level in their movements between said two positions.

5. Apparatus for repeatedly passing pieces or 30 packs of pieces through a sheet or strip mill, comprising in combination with the mill rolls, a set of stock receiving and feeding tables on both sides of said rolls, means for moving each set of tables in a substantially circular path about 35 an axis parallel to but laterally offset from the longitudinal center line of the mill, whereby each table travels from pass level to stock-return level or vice versa without reversing the stock supported thereby.

6. Apparatus for repeatedly passing pieces or 40 packs of pieces through a sheet or strip mill, comprising in combination with the mill rolls, a set of stock receiving and feeding tables on both sides of said rolls, means for moving each table, step-by-step in a substantially circular 45 path, about an axis parallel to but offset laterally from the longitudinal center line of the mill, each table of one set, in successive steps of its movement, arriving in substantial registry with the roll pass and then at a higher or stock-return 50 position, and each table of the other set, in successive steps of its movement, arriving at said higher or stock-return position and then in substantial registry with the roll pass.

7. Apparatus for repeatedly passing pieces or 55 packs of pieces through a sheet or strip mill, comprising in combination with the mill rolls, a set of stock receiving and feeding tables on both sides of said rolls, means for moving each table, step-by-step in a substantially circular path, 60 about an axis parallel to but offset laterally from the longitudinal center line of the mill, each table of one set, in successive steps of its movement, arriving in substantial registry with the roll pass and then at a higher or stock-return 65 position, and each table of the other set, in successive steps of its movement, arriving at said higher or stock-return position and then in substantial registry with the roll pass, and means for coordinating the movements of the tables of 70 the two sets.

8. Apparatus for repeatedly passing pieces or 75 packs of pieces through a sheet or strip mill, comprising in combination with the mill rolls, a set of stock receiving and feeding tables on both

5 sides of said rolls, means for moving each table, step-by-step in a substantially circular path, about an axis parallel to but offset laterally from the longitudinal center line of the mill, each table of one set, in successive steps of its movement, arriving in substantial registry with the roll pass and then at a higher or stock-return position, and each table of the other set, in successive steps of its movement, arriving at said 10 higher or stock-return position and then in substantial registry with the roll pass, and means for maintaining said tables substantially level in their movements between said two positions.

10 9. Apparatus for repeatedly passing pieces or 15 packs of pieces through a sheet or strip mill, comprising in combination with the mill rolls, a set of stock receiving and feeding tables on both

5 sides of said rolls, means for moving each table, step-by-step in a substantially circular path, about an axis parallel to but offset laterally from the longitudinal center line of the mill, each table of one set, in successive steps of its movement, arriving in substantial registry with the roll pass and then at a higher or stock-return position, and each table of the other set, in successive steps of its movement, arriving at said 10 higher or stock-return position and then in substantial registry with the roll pass, means for coordinating the movements of the tables of the two sets, and means for maintaining said tables substantially level in their movements between said two positions.

15 JEROME R. GEORGE.
